CLAIM

The ornamental design for an inkjet printer with stowable media input tray, as shown and described.

DESCRIPTION

FIG. 1 is a perspective view of an inkjet printer with stowable media input tray in accordance with the present invention shown with an input media tray in an operable position for printing;

FIG. 2 is a front elevational view thereof;

FIG. 3 is a top plan view thereof;

FIG. 4 is a rear elevational view thereof;

FIG. 5 is a bottom plan view thereof;

FIG. 6 is a right side elevational view thereof;

FIG. 7 is a left side elevational view thereof; and,

FIG. 8 is a perspective view of the FIG. 1, shown with the input media tray in an alternate stowed position for storage or transport.
